UNITED STATES PATENT OFFICE.

EDWARD B. HESS, OF NEW YORK, AND GEORGE F. HANDLEY, OF GLENDALE, NEW YORK, ASSIGNORS TO ROYAL TYPEWRITER COMPANY, INC., OF NEW YORK, N. Y., A CORPORATION OF NEW YORK.

TYPEWRITING MACHINE.

1,421,083.

Specification of Letters Patent. Patented June 27, 1922.

Application filed September 13, 1921. Serial No. 500,334.

To all whom it may concern:

Be it known that we, EDWARD B. HESS, of Manhattan Beach, Kings County, New York, N. Y., and GEORGE F. HANDLEY, of Glendale, Queens County, L. I., and State of New York, citizens of the United States, have invented certain new and useful Improvements in Typewriting Machines, of which the following is a specification.

10 This invention relates to type actions for typewriting machines, and particularly to the class of type actions in which toggle connections are made between the key levers and the type bars, such connections being so 15 organized that the movement of the type bars is accelerated as the bars move towards the printing point; such actions are commonly used in the Standard Royal machines and are shown in many prior patents, being 20 illustrated, for instance, in Patent No. 1,084, 587, of Jan. 13, 1914.

In such machines the movement of the key levers through flexing and accelerating connections causes the type to move in an arc 25 of approximately 90° directly to the printing point while the type bars abut against a striking plate which serves to assist in stopping the movement of the type bars and to ease the intensity of the impact of the 30 type upon the platen. In such machines considerable noise is made when the type strike the platen and when the type bars impinge on the striking plate.

In United States Patent No. 1,390,708, 35 granted Sept. 13, 1921, to Royal Typewriter Company, Inc., as the assignee of Edward B. Hess, provision is made for eliminating the striking plate usually employed and a new way is shown, described and claimed 40 for connecting the key levers with the type bars which is such that the depression of the keys will cause the type to be raised positively to a point in front of the platen and a considerable distance therefrom and thereafter to be moved into contact with the 45 platen by the momentum of the type bars. This is done each time that a key is depressed and before it has commenced its return movement after depression. In this way, 50 while the type bars are carried upwardly with an accelerated movement this movement is arrested quickly before the type reach the platen while the momentum of the type bars obtained by this accelerated move-

ment causes the type to impinge the platen 51 with reduced force and consequent reduction in noise but with sufficient power to make clear impressions. These results are accomplished without the use of striking plates or stops which have heretofore been a source 60 of noise, and also there are no latches, separable parts or loose connections in the mechanism which would interfere with the positive and reliable operation thereof.

We have found that improved results are 65 obtained if the connections between the key levers and the type bars be made at different points on the heels of the type bars. Inasmuch as the invention is preferably applied to a vertically arranged type bar seg- 70 ment and inasmuch as the type bars normally lie, when at rest, in a substantially horizontal position and are connected to key levers also arranged horizontally, it has been found desirable, in order to bring all the 75 type bars the same distance from the printing point at the beginning of the momentum period, to make the connections between the key levers and the type bars at different points on the heels of the type bars. Thus 80 the type bars in the middle or central portion of the series are connected to the actuating mechanism at certain points relatively to the pivots of the type bars while the type bars on opposite sides of the central bars are 85 connected at different points. In this way the type bars are all brought by substantially uniform touch of the keys first to a substantially uniform position in front of the platen and then by momentum of the 90 type bars are carried to the printing point. By this arrangement not only is noise greatly reduced, but the force of the impact of the type bars on the platen is made substantially uniform.

95 Another feature of the invention is that by this uniform actuation of the type bars a uniform or substantially uniform actuation of the universal bar is obtained.

In the accompanying drawings—
100 Figure 1 is a view, partly in side elevation and partly in vertical section, of portions of a typewriting machine embodying our improvements. This figure of the drawings is largely diagrammatic, many parts of the 105 machine not necessarily concerned with the present invention being omitted.

Figures 2, 3 and 4 are views of the rear

ends of type bars located respectively in the central portion of the machine, in portions of the machine on opposite sides of the center and in the end portions of the machine.

Figure 5 is a diagrammatic view from the underside of the machine, showing a complete set of 42 type bars mounted in a segment, according to our invention the heels 10 of the type bars being shown in section.

Figure 6 is a diagrammatic view, showing another way in which the connections between the heels of the type bars and the actuating mechanism may be made.

15 Figure 7 is a view similar to Fig. 6, showing another modified way of connecting the heels of the type bars to their actuating mechanism.

In Fig. 1, parts of a typewriter carriage 20 are indicated at A and B indicates the platen. A universal bar is shown at C and a type bar segment at D. F indicates a type bar guide. The type bars G have secured to their free ends type blocks G⁴ for 25 carrying upper and lower case printing characters and these type bars are formed with heels g, which are pivotally mounted at d in the type bar segment in the usual way. The type bars extend forwardly from 30 their pivots as usual, their front or type-carrying ends being normally supported by a type bar rest H. The heels of the type bars are connected by links I with the universal bar C, and the return springs J of 35 the type bars are connected to pendant clips j attached to the forward ends of the links I and to the rear support K. The key levers are pivotally mounted at their rear ends in a support M carrying an overhanging dust-shed N and these levers are normally pulled against a cushioned stop O by light springs P extending from the front of the shed to the key levers and connected therewith a short distance in front 40 of their pivots. By adjusting the position of the shed vertically the tension of the springs may be collectively varied. No stops are employed to arrest the downward movement of the levers, this downward 45 movement being cushioned in a manner hereinafter explained. The front links Q are pivotally connected at q with a support R, as heretofore, and each link is connected by a pull rod or pull link S with a heel 50 of a type bar. Each link is connected with the key lever L by a link T, in the usual way.

Most of the features above described and shown in the accompanying drawings are 55 the sole invention of Edward B. Hess, the novel features of our joint invention are hereinafter explained.

It will be observed, by reference to the drawings, that instead of connecting the 60 rear ends of the links S with the heels of

companion type bars at points decidedly in rear of a vertical plane passing through the pivotal connections of the type bars with the segment, they are preferably connected therewith at points below said type 70 bar pivots and, in some instances, approximately in the same vertical plane as the type bar pivots. When this connection was made at the rear of the heel, this point of connection described an arc substantially 75 horizontal or with a horizontal chord, and the type bar was moved with increasing velocity all the way to the platen which it struck with considerable force, producing considerable noise. In the new arrangement 80 the connections between the pull link and the type bar is such as it traverses an arc which is inclined forwardly and upwardly and the connections are such, as before stated, as to cause the type bars to 85 move not all the way to the platen but to a position in front of the platen, the further movement of the type bars to the platen being caused by the momentum of the bars. These features just described are all shown, 90 described and claimed in the application of E. B. Hess, filed July 1, 1921 above referred to.

It will be observed, by reference to the drawings, that when a key is depressed to 95 its greatest extent the pull link S is moved until its point of connection with the heel of the type bar assumes a position in a direct line between the type bar pivot and the point of connection s with the link Q, this 100 operation moving the type bar to the position shown at G⁷, Fig. 1. This is as far as the type bar is positively moved by the key but the momentum of the type bar carries it further until the point of connection between the link S and the type bar assumes the position shown by dotted line x in Fig. 1 and the type bar assumes the dotted position shown in Fig. 1.

Inasmuch as the type bars are mounted 110 in a segment which is arranged vertically, and as the key levers are all arranged horizontally in the keyboard, the connections between the key levers and the type bars vary. We have found that in order to properly 115 move the type bars to accomplish the desired results and to at the same time obtain an equalized movement of the bars and to bring them at the beginning of the momentum period to substantially the same 120 distance from the printing point, the connections between the pull links and the heels of the type bars should be varied, and we have found that the desired results may be obtained by placing the connections 125 of the central type bars and pull links substantially in a vertical plane below their pivots and by placing such connection in the remaining bars at some distance to the rear of said vertical plane. There are va- 130

rious ways in which this can be done. One way is illustrated diagrammatically in Fig. 5 where a complete set of type bars is shown associated with a type bar segment. *d* indicates the pivot rod for the type bars. The curved line *y* indicates the points of connections between the pull links and the heels of the type bars. It will be observed that the line *y* is a curved line as theoretically the points of connections referred to should vary gradually on each side of the central type bars, but sufficiently accurate results can be obtained by arranging the connection points in other ways. Referring to Fig. 6, *x* indicates the pivot line and the points of connections of the type bars are indicated by the lines 1 and 2. In a keyboard containing 42 keys the 22 type bars in the central portion of the machine may have the points of connections with the pull links all made in substantially the same positions, directly under the pivots, while the 11 keys on opposite sides of the central ones should have these connecting points carried to the rear slightly, as indicated. In any case, some of the bars at the central portion of the machine have their points of connections with the pull links beneath the type bar pivots, while some of the bars on opposite sides of the central portion of the machine have these connections carried rearwards slightly.

Another arrangement is shown diagrammatically in Fig. 7. In this figure *x* indicates the pivot line and the points of connections of the type bars to the pull links are indicated by the lines 1, 2 and 3. In a keyboard containing 42 keys, 14 type bars at the center of the keyboard may have the holes where the pull links are connected all arranged in the same line or plane, as indicated at 1 in Fig. 7. 7 type bars at each end of the machine may have said holes all in the same line, as indicated at 3, while each 7 type bars intervening between the end bars and the middle ones may have their points of connections in line with each other, as indicated at 2 in Fig. 7. It will be observed that the lines 2, while in line with each other, are disposed slightly in rear of the line 7, while the lines 3, which are in line with each other, are slightly behind the lines 1 and 2.

The manner in which the connections are made, in accordance with the scheme shown in Fig. 7, is also indicated in Figs. 2, 3 and 4 where it will be observed that the point of connection 1 for a central bar is directly below the type bar pivot. The point of connection to an end bar is disposed at a considerable angle to a vertical line passing through the type bar pivot, while the point of connection to an intermediate bar is at a slightly reduced angle.

As described in the application of E. B.

Hess of July 1, 1921, the connections from the type bars to the universal bar are such that the universal bar is actuated during the momentum period of the type bars; that is, during the time that the type bars accomplish the last part of their excursion to the platen. By our present improvements we have made provision for a uniform actuation of the universal bar; that is to say, one type bar in the series acts upon the universal bar in substantially the same manner as all the others and at substantially the same time in its movement as all the others. This uniformity of operation of the universal bar in connection with the noise-reducing features of the type bar connections is an important feature of the invention.

The invention jointly made by us relates to the arrangement of the points of connection between the type-bar-actuating mechanism and the type bars, all other features of the invention herein shown, described and claimed being shown in the application of E. B. Hess above referred to.

Fig. 1 of the accompanying drawings, as before stated, is largely diagrammatic. Three type bars are shown, one at the middle of the series in a normal, horizontal position, an adjoining one in the position a type bar assumes at the commencement of the momentum period, and a third at the end of the series in a horizontal position. The type bar shown by dotted lines is the same as the second type bar above referred to.

We claim as our invention:—

1. In a typewriting machine a series of type bars having their pivots disposed in the same vertical plane and a series of key levers link-connected with the type bars, some of said links being connected with the type bars at chosen points in the middle of the series and other type bars, on opposite sides of the middle ones, being connected with the links at points in rear of the link-connections at the middle of the series and each of said type bars being moved by the depression of its associated key lever to substantially the same predetermined position in front of the platen and at a considerable distance therefrom, the further movement of each of said type bars from said predetermined position to the platen being caused by its momentum.

2. In a typewriting machine a series of type bars, a series of key levers and a plurality of links connecting each type bar with an associated key lever, some of said links being connected with the key levers and with the associated type bars at chosen points in the middle of the series and other type bars, on opposite sides of the middle ones, being connected with the links at different points in rear of the connections at the middle of the series and each of said type bars being

5 moved by the depression of its associated key lever to substantially the same predetermined position in front of the platen and at a considerable distance therefrom, the further movement of each of said type bars from said predetermined position to the platen being caused by its momentum.

3. In a typewriting machine, a series of type bars, a series of key levers, and type actions interposed between the keys and the type bars, comprising toggle links movable to such an extent by the depression of the keys as to move the type bars to a toggle-locking position in front of the platen and 10 at such a distance therefrom as to reduce noise during the further movement of the type to the platen caused by the momentum of the type bars, said connections between the key levers and the type bars being made 15 at certain points to the middle bars of the series, and at other points to the type bars on opposite sides of the middle ones.

4. A noise-reducing type action for typewriting machines comprising toggle link connections between the type bars and the key levers movable to such an extent by the depression of the keys as to move the type bars to a toggle-locking position in front of the platen and at such a distance therefrom 20 as to reduce noise during the further movement of the type to the platen caused by the momentum of the type bars during which period a short return movement is given to the key levers, the connections between said 25 toggle links and the type bars being made at certain points to the middle bars and at different points to the bars on opposite sides of the middle ones.

5. A noise-reducing type action for typewriting machines comprising toggle link connections between the type bars and the key levers movable to such an extent by the full depression of the keys as to move the type bars to a position in front of the platen and 30 at such a distance therefrom as to reduce noise during the further movement of the type bars to the platen caused by the momentum thereof, said links at the middle 35

portion of the machine being connected to the heels of the type bars immediately beneath the type bar pivots while the heels of the type bars on opposite sides of the central ones are connected to the links in rear of the vertical plane of the type bar pivots. 50

6. In a typewriting machine a vertically arranged type bar segment, a series of type bars normally arranged horizontally, a series of horizontally arranged key levers, and type actions interposed between the keys and the type bars comprising links movable to such an extent by the depression of the keys as to move the type bars to a position in front of the platen and at such a distance therefrom as to reduce noise during the further movement of the type bars about 65 their pivots to the platen caused by the momentum of the type bars, said connections between the key levers and the type bars being made at certain points to the middle bars of the series, at other points to the end bars, 70 and at still other points to the type bars intermediate the middle and the end ones. 70

7. In a typewriting machine the combination with a universal bar and a noise-reducing type action, comprising link connections between the type bars and the key levers movable to such an extent by the full depression of the keys as to move the type bars to a position in front of the platen and at such a distance therefrom as to reduce 75 noise during the further movement of the type to the platen caused by the momentum of the type bars, said links at the middle portion of the machine being connected to the heels of the type bars below their pivots while the heels of the type bars on opposite sides of the middle ones are connected to the links in a plane in rear of the vertical plane of the type bar pivots, and connections between the type bars and the universal bar 80 for operating said universal bar during the momentum period of the type bars. 85

In testimony whereof, we have hereunto subscribed our names.

EDWARD B. HESS.
GEORGE F. HANDLEY.
